ABSTRACT

A JFET circuit generates an adjustable current having a temperature coefficient proportional to I_{DSS} where I_{DSS} is the drain current of a JFET when its source and gate are shorted. The JFET has a source terminal coupled to a source of supply voltage. An adjustable resistor is coupled between the gate and source terminals of the JFET. A reference current is supplied to the resistor, which reference current is proportional to the JFET's pinch-off voltage. The desired current appears at the drain of the JFET.

FIG. 1**FIG. 2**

TRIMMABLE CURRENT SOURCE

BACKGROUND OF THE INVENTION

This invention relates generally to current source circuitry, and more particularly to a junction field effect transistor (JFET) circuit for generating a current (I_D) which is proportional to the saturation current (I_{DSS}) of the JFET and tracks I_{DSS} over temperature.

In an operational amplifier which utilizes JFET followers for driving a PNP differential stage, it is desirable that the JFETs be supplied each with a current equal to I_{DSS} (the drain current when the gate and source are shorted), and in this manner provide a gate to source voltage (V_{gs}) equal to zero and a temperature coefficient equal to zero (i.e. $dV_{gs}/dT = 0$). Furthermore, with V_{gs} on both sides of the amplifier (i.e. V_{gs1} V_{gs2}) equal to zero, the offset voltage V_{os} which equals $V_{gs1} - V_{gs2}$ would be equal to zero as would dV_{os}/dT . Unfortunately, in the past the required current equal to I_{DSS} of the JFET followers could not be assured sufficiency to achieve consistently acceptable results.

SUMMARY OF THE INVENTION

It is an object of the present invention to provide an improved circuit for generating a current which is proportional to I_{DSS} .

It is a further object of the present invention to provide a circuit which generates a current which is proportional to I_{DSS} and which I_{DSS} over temperature.

According to a broad aspect of the invention there is provided a circuit for generating an adjustable current having a temperature coefficient proportional to that of I_{DSS} where I_{DSS} is a drain current of a JFET when its source and gate terminals are shorted, comprising a first JFET having a source terminal coupled to a source of supply voltage, a drain terminal for conducting said current, and having a gate terminal. An adjustable resistor is coupled between the gate terminal and the source terminal, and a current source is coupled to the resistor to causing a current to flow through the resistor so as to develop a voltage across the gate and source terminals.

The above and other objects, features, and advantages of the present invention will be more clearly understood from the following detailed description taken in conjunction with the accompanying drawings, in which:

BRIEF DESCRIPTION OF THE DRAWINGS

FIG. 1 is a schematic diagram of the inventive current generating circuit; and

FIG. 2 is a schematic diagram of a circuit for generating the reference current utilized in FIG. 1

DESCRIPTION OF THE PREFERRED EMBODIMENT

Referring to FIG. 1, the inventive current source comprises a JFET Q1 having a source coupled to a source of supply voltage V_{CC} and having a drain at which the required current I_D is made available. The gate of Q1 is coupled via a trimmable resistor R_T to the source of supply V_{CC} . The gate is also coupled to the source of a reference current I_{REF} .

The reference current I_{REF} may be generated, for example, by the circuit shown in FIG. 2. As can be seen, a second JFET Q2 has a source coupled, via resistor R , to a source of supply voltage V_{CC} . The gate of Q2 is also coupled to V_{CC} . The reference current I_{REF} appears at

the drain of Q2 and is equal to V_P/R where V_P is the pinch-off voltage of Q2. Alternatively, the required reference current I_{REF} could be generated in the manner described in copending patent application Ser. No. 5 SC05987 entitled "CIRCUIT FOR GENERATING A REFERENCE CURRENT PROPORTIONAL TO THE PINCH-OFF VOLTAGE OF A JFET" and assigned to the assignee of the present invention.

Referring again to FIG. 1, I_D may be expressed as

$$I_D = I_{DSS} (1 - V_{gs}/V_p)^2 \quad (1)$$

where V_{gs} is the gate to source voltage of Q1 and V_p is the pinch-off voltage of Q1. Since the source of Q1 is biased above its gate, V_{gs} may be expressed as

$$V_{gs} = -I_{REF} R_T \quad (2)$$

Substituting Equation (2) into equation (1) yields

$$I_D = I_{DSS} (1 + I_{REF} R_T / V_p)^2 \quad (3)$$

As previously described, I_{REF} equals V_p/R . Therefore,

$$I_D = I_{DSS} (1 + V_p R_T / V_p R)^2 \quad (4)$$

As long as JFETs Q1 and Q2 are in close proximity, their pinch-off voltages will be substantially equal and Equation (4) becomes

$$I_D = I_{DSS} (1 + R_T / R)^2 \quad (5)$$

Thus, it can be seen that I_D appearing at the drain of JFET Q1 is proportional to I_{DSS} and may be trimmed simply by altering the ratio of R_T/R . This is accomplished by trimming adjustable resistor R_T . Through this mechanism, I_D may be adjusted so as to be equal to I_{DSS} of the operational amplifier's JFET follower transistor.

If we next assume that resistors R and R_T are of the same type, then the temperature coefficient of R is substantially identical to that of R_T that is

$$dR/dT = dR_T/dT \quad (6)$$

This being the case, the temperature coefficient of I_D is proportional to that of I_{DSS} as is shown in Equation (7).

$$dI_D/dT = (dI_{DSS}/dT) (1 + R_T/R)^2 \quad (7)$$

Thus, the circuit shown in FIG. 1 when driven by a reference current equal to V_p/R produces a current I_D which is proportional to I_{DSS} and trimmable and one which has a temperature coefficient which is proportional to that of I_{DSS} .

The above description is given by way of example only. Changes in form and details may be made by one skilled in the art without departing from the scope of the invention as defined by the appended claims.

I claim:

1. A circuit for generating an adjustable current having a temperature coefficient proportional to that of I_{DSS} where I_{DSS} is a drain current of a JFET when its source and gate terminals are shorted, comprising:

a first JFET having a source terminal coupled to a source of supply voltage, a drain terminal for conducting said current, and having a gate terminal; an adjustable resistor coupled between said gate terminal and said source terminal; and

a current source coupled to said resistor for causing a current to flow through said resistor so as to develop a voltage across said gate and source terminals, wherein said current source generates a cur-

rent proportional to the pinch-off voltage of said first JFET.
2. A circuit according to claim 1 wherein said current source includes at least a second JFET having a pinch-off voltage substantially equal to that of said first JFET.
